ATTORNEYS

UNITED STATES PATENT OFFICE.

PHILIP C. ANDERSON, OF RAPID CITY, SOUTH DAKOTA.

SCRAPER.

Application filed April 30, 1923. Serial No. 635,746.

To all whom it may concern:

Be it known that I, PHILIP C. ANDERSON, a citizen of the United States, and a resident of Rapid City, in the county of Pennington and State of South Dakota, have invented a new and useful Improvement in Scrapers, of which the following is a full, clear, and exact description.

My invention relates to improvements in scrapers, more particularly to scrapers for use on road construction or the like, and it consists in the combination, constructions, and arrangements herein described and claimed.

An object of my invention is to provide a scraper of the bucket type, which is mounted on wheels and which is primarily designed to be drawn by a tractor, novel means being provided whereby the bucket may be easily raised, owing to the fact that the pull of the tractor aids in the raising operation, thereby reducing the labor required to raise a loaded bucket to its carrying position.

A further object of my invention is to provide a novel power means for dumping the bucket at will, said means comprising a clutch mechanism for connecting the dumping mechanism with the axle of the wheels upon which the scraper is mounted.

A further object of my invention is to provide a construction which is comparatively simple, and yet which is strong enough to withstand the rough uses to which such devices are ordinarily put.

Other objects and advantages will appear in the following specification, and the novel features of the invention will be particularly pointed out in the appended claims.

My invention is illustrated in the accompanying drawings, forming part of this application, in which—

Figure 1 is a side elevation of the device;

Figure 2 is a rear elevation;

Figure 3 is a plan view;

Figure 4 is a detail view of the clutch mechanism, and

Figure 5 is a section along the line 5—5 of Figure 4, looking in the direction of the arrows.

In carrying out my invention, I provide a frame, preferably of channel iron and of the shape shown in Figure 3. This frame

includes side members 1 and inclined rear end members 2. At the front end of the frame are upwardly and inwardly inclined frame members 3, which are secured to a guide block or bearing 4. Upper frame members 5 are rigidly secured at their front ends to the guide block 4, and follow the contour of the lower frame members, extending rearwardly and downwardly and being connected with the lower frame members 2 at the rear end (see Figure 1). At this point there is an eye 6 which forms a means for attaching another scraper, so that the scrapers may be drawn in trains.

Pivotedly secured to the lower frame members at 7 are inwardly inclined draw-bars 8 which are connected at their forward ends by means of a clevis 9. This clevis is also rigidly secured to a curved rack or quadrant 10, which passes through the guide block 4, the latter being provided with a roller 11 which bears on the inner curved edge of the rack to guide the parts in their relative movement, as will be explained later.

Toward the rear of the device are uprights 12 bearing a cross member 13, while toward the forward part of the device are rearwardly and inwardly inclined uprights 14 which support a bearing 15. A hand wheel 16 is secured to the end of a shaft 17, which passes through a bearing on the bar 13, thence through the bearing 15. An intermediate shaft 18 is provided with a universal coupling at 19 to connect with the shaft 17, and also with the universal coupling 20 to connect with a stub-shaft 21 bearing a worm at 22, the stub-shaft being journaled in the guide block 4, as shown in Figure 1.

Secured to the lower frame members 1 are bearing blocks 23 (see Figure 1), through which an axle 24 extends. Wheels 25 are mounted on the axle, and it will be noted that these wheels are within the sides of the frame. The wheels are rigidly secured to the axles and turn with the latter. Toward the center of the device the axle 24 is provided with a loosely mounted pinion 26, which is provided with lugs or teeth 27 arranged to engage similar lugs or teeth 28 on a clutch member 29 which is keyed to the axle (see Figure 4). The pinion 26, which, as stated, is loosely mounted on the axle 24, so as to permit the latter to revolve idly within the pinion, is in mesh with a gear 30, which is mounted on a shaft 31 (see

Figure 3) carried by bearings 32 on frame members 33, which are supported on the cross pieces 34.

The means for connecting the gear 30 with the shaft 24, so as to communicate the movement of the shaft to the gear, is best shown in Figures 4 and 5. In these figures it will be observed that the pinion 26 has a grooved portion 35, into which the 10 inturned members of a yoke 36 extend. This yoke is pivotally mounted on a stub shaft 37, having an arm 38 pivotally connected at 39 with a control rod or lever 40, the upper end of which is provided 15 with handles 41. Normally, the lever 40 is held in a lower position, that is to say, to disconnect the pinion 26 from the clutch member 29. To this end a stop member 42 is provided. The upper end of the lever 20 40 is normally underneath the stop member, and is held in such position by means of a spring 43 (see Figure 5). It may, however, be pulled out from under the stop member by swinging it on its pivoted connection, and then when the upper end of 25 the lever has cleared the stop member 42, the spring 44 on the axle will force the pinion 26 into mesh with the clutch member 29, thus imparting the rotary movement of 30 the axle 24 to the gear 30. When it is desired to disconnect the gear 30 from the driving mechanism, the handles 41 are gripped and thrust downwardly and forwardly underneath the stop member. This, 35 through the medium of the arm 38 and the yoke 36, will force the pinion 26 out of engagement with the clutch member 29 against the tension of the spring 44. The parts will be held out of operative position when 40 the lever 40 is underneath the stop member 42.

In front of the wheels is the scraper bucket 45. This, as will be seen from the drawings, is pivotally connected at 7 with 45 the frame portion. The rear end of the bucket is pivotally connected at 46 with a pair of bucket lifting links 47, which are, in turn, connected at 48 with links 49, pivotally secured at 50 on a portion of the frame. A crank arm 51 is pivotally secured to the gear 30 at 52, and to the pivotal connection at 48, where the members 47 and 49 are pivotally connected together.

From the foregoing description of the various parts of the device, the operation thereof may be readily understood. Figure 1 shows the carrying position of the scraper. It is primarily designed to be drawn by a tractor, and it may be lowered by operating the hand wheel 16, for it will be observed that when the hand wheel 16 is turned, the worm 22 will be forced to travel along the rack 10, being guided by the roller 11. The point of attachment 9 cannot move 60 upwardly, so that when the hand wheel is 65

turned clockwise, a buckling movement of the frame with respect to the draw-bars 8 takes place at the pivot 7, which will cause the latter to move downwardly around the axle 24 as a center, and thus swing the 70 bucket in position to scrape up the earth. When it is filled, a reverse movement of the handle 16, together with the pulling force, will cause the loaded bucket to be raised into the carrying position, as shown in Figure 75 1.

The bucket is now drawn along to the dumping position, and when it is desired to dump, the operating lever 40 is pulled rearwardly from the stop member 42 and 80 also upwardly. The spring 24 (see Figure 4) thereupon forces the pinion 26 into engagement with the clutch member 29, as hereinafter described, thus causing the rotation of the gear 30. Assuming that the 85 gears are rotating in a clockwise direction, as shown in Figure 1, the crank arm 51 will be raised from its full line position to the dotted line position, and then will cause the swinging of the links 47 into the 90 dotted line position, thus dumping the load. Further rotation of the crank arm 51 will cause the bucket and the links 47 to resume their normal position, but as the stop member 42, which is carried by the member 47, 95 approaches the carrying position, it will engage the lever 40 and will force it downwardly, thereby disconnecting the pinion 26 from its associated clutch member 29 and stopping the rotation of the gear 30. This 100 occurs, as will be readily understood, when the bucket has reached its carrying position, i. e., the position shown in Figure 1.

These scrapers are designed to be operated in trains, and the pointed ends facilitate the turning of the units of the train in a short radius. With trains of scraper units arranged as described, buckets can be filled one at a time, so that the filling of the buckets does not come all at once on the 110 tractor. Similarly, the dumping of the buckets is accomplished generally one at a time.

The structure described is comparatively simple in that it has relatively few parts, 115 but these are so disposed that they can admirably stand the rough uses to which devices of this kind are subjected.

I claim:

1. A scraper comprising a frame, wheels secured to said frame, a draw bar pivotally secured to the frame at the front end thereof, said frame having an extension projecting forwardly above the draw bar, a bucket carried by the frame, a rack-quadrant secured to said draw bar, a worm carried by said extension and arranged to engage with said rack-quadrant, and means for rotating the worm to cause a relative movement between the draw bar and the extension, 120 125 130

whereby the frame is oscillated about the axis of the wheels, thus raising or lowering the bucket said worm locking said frame in adjusted position.

- 5 2. A scraper comprising a frame, wheels secured to said frame, a draw bar pivotally secured to the frame at the front end thereof, said frame having an extension projecting forwardly above the draw bar, a bucket 10 carried by the frame, a rack-quadrant secured to said draw bar, a worm carried by said extension and arranged to engage with said rack-quadrant, and means for rotating the worm to cause a relative movement between the draw bar and the extension, whereby the frame is oscillated about the axis of the wheels, thus raising or lowering 15 the bucket, said means comprising a hand wheel and operating rods having universal 20 joints, one of said operating rods being connected with the worm wheel shaft said worm locking said frame in adjusted position.

3. A scraper comprising a frame, wheels 25 for supporting said frame, a bucket pivotally secured to said frame, means for tilting said bucket, means for connecting said bucket tilting means to said wheels, whereby said bucket tilting means is actuated by 30 said wheels, said bucket tilting means comprising links, a projection carried by one of said links, a lever for connecting said wheels to said bucket tilting means, said projection being adapted to abut said lever 35 so as to disconnect said bucket tilting means from said wheels after said bucket has been tilted.

4. A scraper comprising a frame, wheels for supporting said frame, a gear carried 40 by said frame, a small gear adapted to be brought into engagement with said first named gear, said small gear being actuated

by said wheels, a bucket, links connecting said first named gear to said bucket, a lever for moving said small gear into and out of engagement with said first named gear, and a projection carried by one of said links and being adapted to engage with said lever so as to throw said lever into inoperative position after said bucket has been tilted. 50

5. In a scraper, a frame, wheels for supporting said frame, a rear axle connecting said wheels together, a gear slidably disposed on said axle, a clutch for connecting said gear to said axle, spring means for moving said gear into engagement with said clutch, whereby said gear is actuated by said axle, a bell crank lever for moving said gear out of engagement with said clutch and a lever connected to said bell crank 60 lever for moving said gear out of engagement with said clutch.

6. In a scraper, a frame, wheels for supporting said frame, a rear axle connecting said wheels together, a gear slidably disposed on said axle, a clutch for connecting said gear to said axle, spring means for moving said gear into engagement with said clutch, whereby said gear is actuated by said axle, a bell crank lever for moving 65 said gear out of engagement with said clutch, a lever connected to said bell crank lever for moving said gear out of engagement with said clutch, a large gear carried by said frame and adapted to be actuated 70 by said first named gear, a bucket carried by said frame, links connecting said bucket to said large gear, and adapted to tilt said bucket when said large gear is actuated, and a projection carried by one of said 75 links and adapted to throw said lever into inoperative position after said bucket has been tilted.

PHILIP C. ANDERSON.
